UNITED STATES PATENT OFFICE.

CHARLES FERNANDEZ, OF SEATTLE, WASHINGTON.

DOOR-CHECK.

1,249,363.

Specification of Letters Patent. Patented Dec. 11, 1917.

Application filed November 20, 1916. Serial No. 132,264.

To all whom it may concern:

Be it known that I, CHARLES FERNANDEZ, a citizen of the United States, and a resident of Seattle, in the county of King and 5 State of Washington, have invented certain new and useful Improvements in Door-Checks,

This invention relates to improvements in door checks, and has for its principal object to provide a generally improved and 10 novel form of door check, whereby a door may be checked and retained in a number of different positions without the necessity of a floor bolt. A further object is to provide coöoperating means, one portion of which 15 is secured to the door frame, and another portion of which is secured to the door. Still a further object is to provide means attachable to a door and to a door frame, where- 20 by when the door is swung upon its hinges its motion is set or retarded at a predetermined number of points in a circle swing. State-room doors on vessels and the like are difficult to retain in an open or semi- 25 open position without some positive means of fastening, chiefly on account of the roll of the ship. My device is intended for use in such cases and offers a semi-positive means for preventing the door from swinging upon 30 either side of the predetermined point of setting the door.

Other objects will appear as my invention is more fully explained in the following specification, illustrated in the accompanying drawings, and pointed out in the appended claim.

Figure 1 is a plan view of a modified form of my device. Fig. 2 is an enlarged sectional elevation of same.

Referring more particularly to the drawings, numeral 1^a will designate the door which is hinged to the frame 2^a. A toothed rack 4^a, similar to rack 4, is secured to frame 2^a and is concentric with respect to the door hinge line. Casing 5^a is secured direct to the face of door 1^a and is provided with up-standing lugs 22 one on either side of rack 4^a. A roller 23 is mounted within lugs 22 and rolls along the top of rack 4^a. The 45 function of the roller is to keep the track in engagement with a pinion 24 which is mounted on a shaft 25 which in turn is

mounted in bearings 26 within the casing 5^a. Levers 27 are secured one to either end of shaft 25 and are set at a slight angle with 55 respect to each other and with respect to a plane which passes through the center line of the shaft 25. Arms 28 are secured adjacent the ends of levers 27 and support the upper ends of springs 29 the lower ends of 60 which are secured to bolts 30. Bolts 30 are adjustably mounted in housing 5^a. In my device, the springs 29 tend to hold the levers 27 in the position as shown and act somewhat against each other in this position due to 65 the angularity of the levers. When the door is swung in either direction the pinion 24 is made to revolve with the result that the springs are elongated and therefore tend to remain in their normal position. The ten- 70 sion of the springs is sufficient to resist the ordinary tendency of the door to swing and it will require some little shove to move the door from normal position. It will be apparent that there is a normal or holding 75 position for the door in every revolution of the pinion 24. I also provide a night latch 31 which is pivoted to casing 5^a as at 32. The lower end of the night latch projects 80 through a slot in the casing and may be operated by the hand from the inside of the door. When the night latch is shoved to the right the upper end engages the teeth of the pinion 24 and prevents the pinion from re- 85 volving, thereby preventing the door from being swung in either direction. The night latch is of particular advantage on steamers and the like where it is desired to leave the door slightly ajar but locked against entrance.

While I have shown a particular form of embodiment of my invention, I am aware that many minor changes therein will readily suggest themselves to others skilled in the art without departing from the spirit 95 and scope of the invention, and I therefore desire to avoid being limited to the exact claim.

Having described my invention, what I claim as new and desire to protect by Letters Patent, is—

In a device of the class described, the combination of means for automatically checking a door at a plurality of predeter-

mined positions, said means including a toothed rack mounted upon the door frame concentrically with the hinge line of the door, a pinion secured to a shaft and mounted upon the door and engaging the said rack, levers secured to either end of the pinion shaft and disposed at an angle to each end

and tension springs one end of each of which is secured to the said levers, whereby when the door is swung on its hinges the movement of the levers will increase the tension of the springs which will tend to hold the door in normal position. 10

CHARLES FERNANDEZ.
